US00D828028S

(12) **United States Design Patent** (10) **Patent No.:** **US D828,028 S**
(45) **Date of Patent:** **** Sep. 11, 2018**

(54) **CONTAINER**

(71) Applicant: **YETI Coolers, LLC**, Austin, TX (US)

(72) Inventors: **Roy Joseph Seiders**, Rollingwood, TX (US); **Steve Charles Nichols**, Austin, TX (US); **Kyle Ellison**, Austin, TX (US); **Andy Bondhus**, Austin, TX (US); **Tobias Hotchkiss**, Austin, TX (US); **Liza Morris**, Austin, TX (US); **Dennis Zuck**, Austin, TX (US); **Ryan Nixon**, Austin, TX (US)

(73) Assignee: **YETI Coolers, LLC**, Austin, TX (US)

(**) Term: **15 Years**

(21) Appl. No.: **29/607,291**

(22) Filed: **Jun. 12, 2017**

(51) LOC (11) Cl. **03-01**

CLAIM

The ornamental design for a container, as shown and described.

DESCRIPTION

FIG. 1 is a top, front, right perspective view of a container showing our new design in an open configuration; FIG. 2 is a front view thereof; FIG. 3 is a rear view thereof; FIG. 4 is a right side view thereof; FIG. 5 is a left side view thereof; FIG. 6 is a top view thereof; FIG. 7 is a bottom view thereof; FIG. 8 is a top, front, right perspective view of a container showing our new design in a closed configuration; FIG. 9 is a front view thereof; FIG. 10 is a rear view thereof; FIG. 11 is a right side view thereof; FIG. 12 is a left side view thereof; FIG. 13 is a top view thereof; and, FIG. 14 is a bottom view thereof.

The broken-lines illustrate portions of the container and form no part of the claimed design.

1 Claim, 14 Drawing Sheets
